UNITED STATES PATENT OFFICE.

LOUIS E. ISELE, OF GLENRIDGE, NEW JERSEY, ASSIGNOR TO BEAVER MACHINE & TOOL COMPANY, OF NEWARK, NEW JERSEY, A CORPORATION OF NEW JERSEY.

SOCKET TERMINAL.

Application filed February 4, 1922. Serial No. 534,017.

To all whom it may concern:

Be it known that I, LOUIS E. ISELE, a citizen of the United States, residing at Glenridge, in the county of Essex, State of New Jersey, have invented an Improvement in 5 Socket Terminals, of which the following is a specification.

This invention relates to a socket terminal and more particularly to that type of 10 socket terminal employed in switch or other plugs adapted for use in connection with electric irons and other similar utensils in which as commonly constructed there are stud terminals to be received by the socket terminals. Heretofore in terminals of the 15 type to which my invention relates, difficulties have been experienced in making good contacts between the plug terminals of the iron or other similar apparatus and the 20 sockets of the switch plug adapted to be connected therewith. These difficulties have arisen largely because of the fact that the socket terminals as commonly constructed have not been adapted to accommodate 25 themselves to various conditions, as well as positions in which the plug terminals may be found.

The object of my present invention is to 30 overcome these difficulties by providing a socket terminal, the parts of which are shiftable to position relatively to one another to accommodate themselves to the positions and conditions of the plug terminals, as well as to make a substantial contact extending for 35 practically the entire length of the plug terminal, as will be hereinafter more particularly described.

In the drawing:

Fig. 1 is a plan of one member of a switch 40 plug, showing the parts associated therewith, including the socket terminals which comprise my present invention.

Fig. 2 is a front view on an enlarged scale, showing the improved socket terminal.

Fig. 3 is an edge view of the same.

Fig. 4 is a section taken on line 4—4, Fig. 2, and

Fig. 5 is an end view of the socket terminal.

Referring to the drawing, I have illustrated 50 my invention as used in a switch plug, although of course it will be understood that its use is not so limited as it may be employed with numerous other and similar devices.

As illustrated, however, one member of

the switch plug casing is indicated at 10. This is provided interiorly with a recess 11, adapted to receive the base 12 of a switch mechanism. This switch mechanism is operated by reciprocating buttons 13, and the 60 base is provided with contacts 14 and 15, by and through which the electric circuit may be closed through a suitable oscillating member operated by the buttons 13. The contact 14 is connected to a conductor 16 provided with a suitable binding post and there is also a conductor 17, extending beneath the base 12 of the switch mechanism, and fitted with a binding post to which and the binding post associated with the conductor 16 65 the lead wires are connected after having been passed through an opening provided at the end of the casing by a recess portion 18. The contact 15 is connected to a terminal 19 and the opposite end of the conductor 17 is connected to a terminal 20, while the terminals 19 and 20 are connected to the socket terminals, forming the present invention, these socket terminals being adapted to fit and lie within the recesses 21 70 and 22, provided therefor in the casing.

The casing and switch mechanism, however, form no part of my present invention. The socket terminal construction, to which the present invention relates, consists in a 85 leaf 23 which is fixed to or integral with a head 24 having an opening 25 and oppositely disposed flanges 26, by which the head may be fitted over and connected to either of the terminals 19 or 20 by a suitable screw or 90 otherwise.

The leaf 23 is provided with oppositely disposed flanges 26 and 27 employed in pairs, as clearly indicated, and having in-turned fingers 28 at the extremities thereof. 95 Extending between, and lying immediately beneath the in-turned fingers 28 is a spring, or resilient member 29. This, as illustrated, is substantially H-shaped, so that the extremities thereof may engage with the inner surfaces of the in-turned fingers 28. In a centrally disposed position the spring 29 is fitted with an inwardly extending boss, 30 which may be stamped therein, as shown, or attached thereto in any desired manner. 105

I also employ a movable or yielding leaf member 31. This is centrally ribbed as indicated at 32 and is provided with a recess, or opening 33 to receive the boss or projection 30 of the spring, upon which the mov- 110

able or yielding member is pivotally mounted and by which it is retained in position, that is, it is prevented from shifting either laterally or longitudinally, relatively to the 5 fixed leaf 23, but is permitted to swing about the boss 30 in any direction, so as to cause the yielding or movable leaf to be turned to accommodate the plug terminal of an iron or other device irrespective of 10 the shape or cross section of the plug terminal or its direction, relatively to the plug terminal with which it may be associated.

It will thus be seen that even if the plug terminals are not in alignment and whether 15 they are round or rectangular, the socket terminal made in accordance with this invention will not only accommodate itself to various conditions in use, but will also provide a contact which extends for the 20 entire length of the plug terminal, or that portion thereof which is inserted in the socket terminal.

I claim as my invention:

1. A socket terminal comprising a fixed 25 leaf, lugs at the sides thereof, adjacent the ends and terminating in inturned fingers, substantially parallel to the body of the fixed leaf, a resilient member maintained in position by the said lugs and fingers,

and a movable leaf pivotally connected centrally to the said resilient member.

2. A socket terminal, comprising a fixed leaf, sets of lugs adjacent the ends of the said fixed leaf at right angles thereto, and terminating in fingers substantially parallel 35 with the body of the fixed leaf, a spring member having a centrally disposed boss, and a movable leaf having a centrally disposed recess adapted to receive the boss of the spring member to pivotally connect the 40 said movable leaf to the spring member.

3. A socket terminal comprising a fixed leaf having a centrally disposed longitudinal rib, lugs turned at right-angles to the body of the fixed leaf adjacent the ends 45 thereof and terminating in fingers lying substantially parallel to the body of the fixed leaf, an H-shaped spring secured in position by the said fingers and having a centrally disposed boss on the inner surface thereof, 50 and a movable leaf also having a centrally longitudinal rib in which there is a recess to receive the boss on the spring in order to pivotally connect the said movable leaf to the said spring.

Signed by me this 19th day of November 1921.

LOUIS E. ISELE.
